(57) CLAIM

The ornamental design for a self-defense necklace pendant, as shown and described.

DESCRIPTION

FIG. 1 is a perspective view of a self-defense necklace pendant, showing the new design;

FIG. 2 is a front elevational view thereof;

FIG. 3 is a rear elevational view thereof;

FIG. 4 is a left-side elevational view thereof, the right-side elevational view being a mirror image thereof;

FIG. 5 is a top plan view thereof; and,

FIG. 6 is bottom plan view thereof.

The broken lines represent environmental structure as well as portions of the self-defense necklace pendant that form no part of the claimed design.
